UNITED STATES PATENT OFFICE.

ISIDOR LESEM, OF WICHITA, KANSAS.

CARRIER FOR EGGS AND THE LIKE.

1,323,074.

Specification of Letters Patent. Patented Nov. 25, 1919.

Application filed June 20, 1916. Serial No. 104,746.

To all whom it may concern:

Be it known that I, ISIDOR LESEM, a citizen of the United States, residing at Wichita, in the county of Sedgwick and State of 5 Kansas, have invented a new and useful Carrier for Eggs and the like, of which the following is a specification.

This invention relates to a carrier for eggs, and other fragile objects such as incandescent lamps and the like, one of the objects of the invention being to provide a cellular filling for boxes or other forms of containers, the cells being formed of interfitting partition strips having opposed walls 10 so shaped as to receive and support opposed portions of objects placed in the cells, additional means being employed for closing the ends of the cells and at the same time cushioning the contained objects should they be 15 come displaced from their normal positions.

Another object is to provide a carrier which will hold the maximum number of eggs or the like suspended in the minimum space, the structure being equally useful for 20 the largest freight or express shipment as for a parcel post carrier.

A further object is to provide a carrier all parts of which can be readily cut from cardboard or like material and which carrier is 25 cheap to manufacture and affords ample protection to the contents thereof, thus rendering the structure particularly useful when shipping articles by parcel post.

With the foregoing and other objects in 30 view which will appear as the description proceeds, the invention resides in the combination and arrangement of parts and in the details of construction hereinafter described and claimed, it being understood 35 that changes in the precise embodiment of the invention herein disclosed, can be made within the scope of what is claimed, without departing from the spirit of the invention.

In the accompanying drawings the preferred form of the invention has been shown.

In said drawings:—

Figure 1 is a horizontal section through a portion of a carrier embodying the present 50 improvements, eggs being shown in position within the cells.

Fig. 2 is a section on line A—B Fig. 1, eggs being shown in certain of the cells.

Fig. 3 is a plan view of a portion of one

of the partitions designed to be placed between the cellular trays of the carrier. 55

Fig. 4 is a horizontal section through a portion of a tray and showing a modified form of cushioning partition to be used in lieu of the partition shown in Fig. 3. 60

Referring to the figures by characters of reference 1 designates parallel partition strips intersecting substantially parallel partition strips 2 disposed at right angles thereto, the strips 1 and 2 coöperating to 65 form article receiving cells 3 and extending around spaced cells 4. The spacing cells permit the walls of the cells 3 to yield outwardly and thus cushion the contents of the cells when the carrier is subjected to rough 70 handling. The partition strips 2 are provided with openings 5 so that each cell 3 will have two diametrically opposed openings. The distance across each cell and between the strips 2 is preferably slightly less than 75 the diameter of the object to be held so that, when said object is placed in the cell 3, as indicated at 6, it will cause the strips 2 to bend outwardly and will also cause the opposed side portions of the contained object to project into openings 5. The walls of these openings will thus press yieldingly 80 against the object 6, and hold said object centered within the cell 3.

The intersecting strips 1 and 2 form cellular trays adapted to be placed one above the other in a box or other form of container, a portion of which has been shown at 7 and a partition 8 may be disposed between adjoining trays. This partition, a portion of 85

which has been shown in Fig. 3, is preferably formed of a single sheet of cardboard having groups of incisions so disposed that one group will be located in line with the longitudinal center of each cell. In each 90

group of incisions are provided opposed arcuate slits 9 from the ends of which extend parallel slits 10 so that a substantially circular cushioning member 11 is thus provided 95

with oppositely extending tongues 12 which connect it to the body portion of the partition 8. Slits 13 radiate within the partition 8 from the arcuate slits 9 and crossed slits 14 may be provided in the center of the cushioning disk 11. When an article is held 100

within a cell by the apertured walls or strips 2, the ends of the article will not ordinarily engage cushioning disks 11. However, 105

should the article become displaced within the cell because of rough handling, one end thereof would come against the adjacent cushioning disk 11 which would yield and 5 thus cushion the object and prevent it from breaking. Where the cells are used for holding incandescent lamps, the pointed tips usually provided at the ends of the lamps can be held within the cushioning disks 11 10 where the slits 14 cross.

Where only one tray is to be used in a container, it is not always desirous to use a partition 8 at the top and bottom thereof. Instead slots 15 are formed in each strip 2 15 above and below the openings 5 and these slots are adapted to receive partition strips 16 extending transversely of the tray and each of which has groups of incisions 17 such as shown in Fig. 3, one group being 20 located in line with the center of each cell.

Importance is attached to the fact that the carrying or holding cells are grouped about the spacing cells 4 as it is thus possible to ship about twice as many eggs in the same

space, as can be done with the ordinary cellular carrier wherein the spacing cells are 25 extended around the holding cells.

What is claimed is:—

A carrier of the class described including a cellular structure for holding eggs, and a 30 partition closing one end of each egg receiving cell, said partition having slits forming egg supporting strips provided with substantially circular portions each located at the center of the end of a cell, there being 35 crossed slits in said portion forming segmental egg supporting flaps, there being also radial slits within the partition and extending outwardly from said circular portion to form supplemental cushioning and 40 centering flaps.

In testimony that I claim the foregoing as my own, I have hereto affixed my signature in the presence of two witnesses.

ISIDOR LESEM.
